UNITED STATES PATENT OFFICE

CHARLES GUSTAV MELLSTROM, OF WESTMINSTER, LONDON, ENGLAND, ASSIGNOR TO
VICKERS LIMITED, OF LONDON, ENGLAND, A BRITISH COMPANY

PROJECTILE FUSE

Application filed April 5, 1928, Serial No. 267,511, and in Great Britain May 7, 1927.

This invention relates to projectile fuses and has for its chief object to devise an improved fuse which will operate satisfactorily on graze as well as on impact.

5 According to the invention a spring controlled firing element is normally held in its retracted position by a retaining member which is so constructed and arranged that when the spin of the projectile is retarded as 10 a result of the projectile grazing an object, the rotational inertia of the said member will cause it to move into the releasing position to enable the firing element to operate. This retaining member may be in the form of a 15 pivoted arm the pivot of which is parallel to and at one side of the axis of the fuse and the portion of the arm opposite the said pivot is weighted to such an extent that when the spin of the projectile is normal and unchang- 20 ing, or is only changing slowly, there is a centrifugal bias tending to keep the said arm in its retaining position, the amount of centrifugal bias in this direction being kept as low as is practicable. The said arm may also 25 be positively locked in this position, until the projectile has been fired from the gun by a centrifugal locking bolt which in turn is held in the locking position by an inertia detent. On shock of discharge this detent 30 moves rearwards against the resistance of a spring and the spin of the projectile then causes the locking bolt to move into the releasing position. When the forward acceleration of the projectile ceases the detent is 35 returned by its spring and passes in front of the inner portion of the centrifugal locking bolt and thus prevents the latter from returning to its locking position.

40 The other firing element (i. e. that for cooperating with the firing element normally held in the retracted position by the retaining member) may be carried by a block or pellet which on impact (as distinct from a mere graze) of the projectile with an obstruction, moves forward by its momentum to fire the detonator cap carried by one of the said 45 firing elements.

In order that the said invention may be clearly understood and readily carried into effect, the same will now be described more

fully with reference to the accompanying drawings in which:—

Figure 1 is a side elevation of a fuse in accordance with this invention.

Figure 2 is an axial section of the fuse, 55

Figure 3 is a section taken approximately on the line 3, 3 of Figure 2,

Figure 4 is a plan on a larger scale than Figures 1 to 3, of the firing element that moves forward by momentum on impact, the 60 firing needle being in the unarmed condition.

Figure 5 is a section taken approximately on the line 5, 5 of Figure 4,

Figure 6 is a section taken approximately 65 on the line 6, 6 of Figure 5, and

Figures 7 and 8 are views similar to Figures 5 and 6 showing the firing needle in the armed condition.

A is the fuse body provided with a screwed collar A¹ which receives a cap A² at its outer end. B is the detonator cap holder (constituting one of the firing elements of the fuse) slidably disposed in an axial recess in the collar A¹. Between this holder and the cap A² 70 is arranged a helical spring B¹ which, when the holder is released as will be described hereinafter, impels the said holder rearwards to explode the detonator cap B². In the particular construction shown the other firing element is of known type and comprises a block or pellet C which is slidably mounted in an axial recess in the rear part of the fuse body and carries a needle member C¹ pivoted at C² and normally held in a safe position 75 with the needle C² out of line with the detonator cap B² by centrifugal locking bolts C³, C⁴. These locking bolts are moved outwards 80 into their releasing position (Figure 8) as a result of the spin of the projectile and the member C¹ carrying the firing needle C² is so constructed that when released it moves under the action of centrifugal force from its housed position (Figures 4 to 6) into a position to bring the needle in line with the detonator cap (Figures 7 and 8). The block or pellet C carries forwardly extending 85 spring plungers C⁴ which prevent forward creeping movement of the block or pellet. When however the shell strikes (as distinct 90

95 from a mere graze) of the projectile with an obstruction, moves forward by its momentum to fire the detonator cap carried by one of the said firing elements. When however the shell strikes (as distinct 100

from merely grazing) an obstruction the block or pellet C moves in a forward direction by momentum to bring the firing needle C² into contact with the detonator cap B².
 5 The detonator cap holder B is also at the same time released as will be described owing to the cessation of the spin of the projectile, but the firing of the detonator cap on impact of the projectile with an obstruction is not
 10 dependent upon the release of the detonator cap holder.

D is the aforesaid retaining member for normally holding the spring controlled detonator cap holder B in the retracted position shown in Figure 2. This member is in the form of an arm of curved formation (see Figure 3) pivoted to the fuse body by means of a pin D¹ arranged parallel to and at one side of the axis of the fuse. The middle portion of the said arm engages beneath a shoulder B³ on the detonator cap holder B as shewn in Figure 2 and the portion of the said arm opposite the pivot pin D¹ is enlarged as shown so that the centre of mass of the said arm D is situated on that side of a plane passing through the axis of the pivot pin D¹ and the axis of the fuse, which approaches a stop D^x (as indicated by the dotted line in Figure 3) such that when the spin of the projectile is
 20 normal and unchanging (or only changing slowly) the effect of centrifugal force is to tend to turn the arm D about the pivot pin D¹ in a clockwise direction in Figure 3 and therefore to hold the said arm in its retaining position. This action is assisted by a small leg spring D². It will be seen that the arm D is arranged at the side of the holder D such that when spin is imparted to the projectile by the rifling of the
 25 gun barrel, the inertia of the said arm holds the latter in the retaining position in contact with the stop D^x (Figure 3). The said arm is positively locked in the retaining position, until the projectile has been fired from the
 30 gun, by a centrifugal locking bolt E which is disposed in a recess in a plug E¹ in the side of the fuse body and engages in a hole in the foresaid enlarged portion of the arm D. This locking bolt is normally locked in its engaging position by a longitudinally arranged and spring controlled inertia detent E². On
 35 shock of discharge this detent moves rearwards and unlocks the bolt E which then moves outwards under the action of the spin of the projectile to unlock the arm D. When the forward acceleration of the projectile ceases the spring of the detent E² returns the latter so that it is situated at the inner side of the bolt E and the latter is thereby prevented from returning to its locking position. The arm D is thus free so that when the projectile grazes an object and its spin is, in consequence, reduced, the said arm is moved about its pivot pin D¹ in an anti-clockwise direction (Figure 3) by reason of its rotational

inertia, thereby releasing the detonator cap holder B which is thereupon impelled by its spring B¹ to bring the detonator cap B² into forcible contact with the firing needle C² which has already moved into the position shown in Figures 7 and 8 as previously described.

Although the needle member C¹ has been described as being carried by a block or pellet C which, on impact of the projectile with an obstruction, moves forwardly to bring the needle against the detonator cap B², the said needle member can be carried by a fixed part in which case the stoppage of the spin of the projectile on impact is relied upon to release the detonator cap holder B as has been described above in regard to what occurs when the projectile grazes an object.

What I claim and desire to secure by Letters Patent of the United States is:—

1. In a projectile fuse the combination with a spring controlled firing element, of a retaining member for said element, and means for mounting said member so that it moves in a plane transverse to the longitudinal axis of the fuse, by rotational inertia when the spin of the projectile is retarded as a result of the projectile grazing an object, and means whereby the movement of said member by rotational inertia releases said firing element.

2. In a projectile fuse the combination with a spring controlled firing element, of a retaining member for said element, and means for rotatably mounting said member so that it moves angularly in a plane transverse to the longitudinal axis of the fuse, by rotational inertia when the spin of the projectile is retarded as a result of the projectile grazing an object and means whereby the movement of said member by rotational inertia releases said firing element.

3. In a projectile fuse the combination with a spring controlled firing element, of a retaining arm for said element and means for pivoting said arm so that it turns about an axis parallel to the longitudinal axis of the fuse, into its releasing position, by rotational inertia when the spin of the projectile is retarded as a result of the projectile grazing an object.

4. In a projectile fuse, the combination with the elements claimed in claim 3, of means for weighting the portion of the arm opposite its pivot to such an extent that when the spin of the projectile is normal and unchanging or is only changing slowly, there is a centrifugal bias tending to keep the said arm in its retaining position.

5. In a projectile fuse, the combination with the elements claimed in claim 3, of a centrifugal locking bolt which engages with the retaining member to lock it in the retaining position until said bolt is moved by centrifugal force to the disengaging position.

6. In a projectile fuse, the combination with the elements claimed in claim 3, of a centrifugal locking bolt which engages with the retaining member to lock it in the retaining position until said bolt is moved by centrifugal force to the disengaging position and an inertia detent normally holding the locking bolt in the locking position.

7. In a projectile fuse, the combination with the elements claimed in claim 3, of a centrifugal locking bolt which engages with the retaining member to lock it in the retaining position until said bolt is moved by centrifugal force to the disengaging position, an inertia detent normally holding the locking bolt in the locking position, and a spring which, after the forward acceleration of the projectile ceases, moves said detent into a position in front of said locking bolt so as to prevent the latter from returning to its locking position.

8. In a projectile fuse, the combination with the elements claimed in claim 1, of a second firing element carried by a member which on impact (as distinct from a mere graze) of the projectile with an obstruction, moves forward by its momentum to fire the detonator cap carried by one of said firing elements.
